UNITED STATES PATENT OFFICE.

CASPER A. PETERSON, OF DEMMON, MICHIGAN.

BASE-BALL GLOVE.

No. 906,278.

Specification of Letters Patent.

Patented Dec. 8, 1908.

Application filed April 10, 1908. Serial No. 426,338.

To all whom it may concern:

Be it known that I, CASPER A. PETERSON, a citizen of the United States, residing at Demmon, in the county of Houghton and 5 State of Michigan, have invented new and useful Improvements in Base-Ball Gloves, of which the following is a specification.

This invention relates to base ball gloves or mitts, and the object of the invention is to 10 provide a glove with a web positioned between the fingers of the glove whereby a large area is afforded a player catching a ball, and whereby the liability of injuring the fingers of the player is greatly lessened.

15 A still further object of the invention is to provide a base ball glove with a web positioned away from the point of juncture of the fingers of the glove whereby a small resistance of air will be met as the player manipulates the glove through the air in the act of catching or stopping a ball.

To these ends the invention resides in the novel construction of base ball gloves, herein-after fully described and claimed.

25 The accompanying drawing illustrates an ordinary base ball glove provided with my improvement.

In the drawing the numeral 1 designates an ordinary base ball glove. This glove 1 30 may be padded as illustrated in the drawing and is adapted to have its fingers 2 connected by a flexible web 3. The web 3 may be of any desired or preferred material, and may be attached to the fingers of the glove in any 35 desired manner. The webs 3 are adapted to be connected to the fingers 2 of the glove at a suitable distance away from the point of connection of the fingers with the body of the glove so as to provide air spaces 4, between 40 the meeting points of the fingers and the edge of the webs 3. The opposite ends of the webs 3 terminate with the ends of the fingers and thumb of the glove, and are preferably scalloped or in cut as illustrated in the draw- 45 ing.

By this construction it will be readily seen that I have provided an attachment for base ball gloves which not only enables the player to catch or stop a ball easily but also provides air passages between the fingers and 50 the point of juncture of the fingers whereby a small resistance is offered as the player swings the glove through the air when catching or stopping a ball. It will be further noted that by providing the outer edges of 55 the webs with scallops or incuts no projecting portion of the web is presented to interfere with the manipulation of the player in the act of catching a ball whether the fingers be folded together or expanded. It will be 60 still further seen that by providing a base ball glove with my improvement danger to the player is greatly reduced as the webs prevent the fingers being separated from each other as would occur should a ball contact 65 with one of the fingers of an ordinary glove.

Having thus fully described the invention what is claimed as new is:

1. A base ball glove having a flexible web between its fingers and thumb, said web being connected with each of the adjoining fingers and terminating between the fingers away from their point of connection with the body of the glove to provide air passages whereby a partial resistance to the air is afforded as the glove is manipulated. 70

2. A base ball glove having a flexible web between its fingers and thumb, said web being scalloped at its upper connection with the fingers and thumb of the glove, and said 80 web being connected with each of the adjoining fingers of the glove and terminating between the fingers away from their point of connection with the body of the glove.

In testimony whereof I affix my signature 85 in presence of two witnesses.

CASPER A. PETERSON.
